US0D1025122S

(12) **United States Design Patent** (10) **Patent No.:** **US D1,025,122 S**
(45) **Date of Patent:** **** Apr. 30, 2024**

(54) **DISPLAY SCREEN OR PORTION THEREOF WITH GRAPHICAL USER INTERFACE**

(71) Applicant: **Apple Inc.**, Cupertino, CA (US)

(72) Inventors: **Jonathan Cho**, San Francisco, CA (US); **Daniel Huy Mai**, Cupertino, CA (US); **Wyatt R. Mitchell**, San Francisco, CA (US); **Lorraine Sohee Shim**, Santa Clara, CA (US)

(73) Assignee: **Apple Inc.**, Cupertino, CA (US)

(**) Term: **15 Years**

(21) Appl. No.: **29/884,413**

(22) Filed: **Feb. 10, 2023**

Related U.S. Application Data

(63) Continuation of application No. 29/822,669, filed on Jan. 11, 2022, now Pat. No. Des. 978,192, which is a continuation of application No. 29/746,021, filed on Aug. 11, 2020, now Pat. No. Des. 941,869, which is a continuation of application No. 29/640,650, filed on Mar. 15, 2018, now Pat. No. Des. 905,718.

(57) **CLAIM**

The ornamental design for a display screen or portion thereof with graphical user interface, as shown and described.

DESCRIPTION

The sole FIGURE shows a display screen or portion thereof with graphical user interface showing our new design. The peripheral dashed broken lines illustrate a display screen or portion thereof, and form no part of the claimed design.

1 Claim, 1 Drawing Sheet
